Primary Examiner — Garth Rademaker*Assistant Examiner* — Melanie Pellegrini(74) *Attorney, Agent, or Firm* — Locke Lord LLP; Howard M. Gitten(57) **CLAIM**

The ornamental design for a hoop earring, as shown and described.

DESCRIPTION

FIG. 1 is a front and right side perspective view of a hoop earring, in accordance with the invention;

FIG. 2 is a top plan view thereof;

FIG. 3 is a front elevational view thereof;

FIG. 4 is a right side elevational view thereof;

FIG. 5 is a rear elevational view thereof;

FIG. 6 is a left elevational view thereof; and,

FIG. 7 is a bottom plan view thereof.

The broken lines shown in the drawings illustrate portions of the hoop earring that form no part of the claimed design.

1 Claim, 2 Drawing Sheets(56)
